TIME LAPSE INDICATOR

John C. Van Aken, 159 Main St., Ridgway, Pa.

Filed Dec. 3, 1959, Ser. No. 857,078

3 Claims. (Cl. 340—43)

This invention relates to automatic street traffic signals and is particularly concerned with modifying such signals in a manner to provide safety measures for pedestrian traffic.

Street traffic signals in general utilize a yellow or amber light between changes of the red and green signals. The purpose of the yellow or amber light is to warn or caution all traffic that a change from red to green or from green to red will take place in a short period usually in a matter of seconds. This short warning or caution period is often of no avail to pedestrian traffic caught midway of a cross walk since motor traffic may proceed on an anticipated green signal before the pedestrian traffic is clear of the intersection which, of course, results in inconvenience, confusion and possibly accidents.

It is the broad object of this invention to supplement the usual traffic light signal system with a timing device which may indicate to pedestrian traffic whether or not there is sufficient time to cross an intersection in safety.

Another object is to provide an auxiliary housing containing time lapse mechanism and which is readily attachable to street traffic signals.

Another object is to provide an auxiliary housing containing a compact arrangement of time lapse indicating mechanism.

Still another object is to provide a time lapse device which may be relatively inexpensively produced but provides an accurate time lapse indicator.

Other and more detailed objects of the invention will be apparent from the following detailed explanation of the invention.

Referring to the drawings wherein:

FIG. 1 is a view in elevation showing diagrammatically the device of the present invention attached to a street traffic signal.

FIG. 2 is a plan view of the assembly of FIG. 1.

FIG. 3 is an enlarged vertical sectional view of the device of the present invention.

FIG. 4 is a view similar to FIG. 3 taken at 90° thereto.

FIG. 5 is a sectional view taken on the line 5—5 of FIG. 4.

FIG. 6 is a schematic view of the apparatus of FIG. 1 and showing a wiring arrangement for synchronizing the operation of the main traffic signal with the auxiliary time lapse indicator lights.

FIG. 7 is a modification of the time lapse mechanism adapting the device for other uses.

Referring to FIGURES 1 and 2, the numeral 10 indicates a conventional street traffic signal structure having signal lights therein which are represented at G and R as the respective "Go" and "Stop" signals and containing their operating electrical equipment. The traffic signal 10 is usually supported on a tubular standard 11 and power from a source is supplied to the signals G and R through suitable connecting lines enclosed in the standard 11 to supply power from a source. The above general structure is well known and is indicated by phantom lines while the device of the present invention is shown diagrammatically in FIG. 1 in full lines as an attachment to the old structure.

The time lapse device of this invention is in the form of an elongated rectangular or oblong shaped housing 12, of metal or other material to withstand weathering, which is readily attachable to the traffic signal structure 10 through bolt connections 13—13 and contains the time lapse indicating equipment which is readily visible through

2

transparent front face 14 to an observer along with the street traffic signals G and R. The front face 14 is generally arcuately shaped in transverse cross section and is removably secured to the housing 12 by bolt connections 15—15.

Detailed construction of the time lapse indicator is shown in FIGS. 3, 4 and 5 and the various elements are selected and arranged to provide a rugged relatively inexpensive and yet an accurate indicating mechanism. The auxiliary housing 12 provides an elongate rectangular or oblong compartment formed of side walls 20 and 21, rear wall 22 with upper and lower ends 23 and 24 respectively and the plastic transparent front face 14. A U-shaped carriage 25 for mounting other elements is located within the compartment and is arranged to be movable longitudinally thereof between the housing ends 23 and 24. The carriage 25 is formed conveniently of non conducting material such as a molded plastic and has a top plate 26 and a bottom plate 27 which provide a sliding and guiding fit with side walls 20 and 21 of the auxiliary housing 12. A lead screw 28 has its upper end 29 rotatably mounted in the upper end 23 of housing 12 and its lower end 30 rotatably mounted in an L-shaped bracket 31 which is fixed to the housing rear wall 22 by screws 32 and provides a space 33 with the housing lower end 24. The lead screw 28 is of rigid construction and extends through threaded apertures in the top and bottom plates 26 and 27 of the carriage 25 providing an arrangement, on rotation of lead screw 28, for raising or lowering the carriage 25 as is well known in the art. For the purpose of rotating the screw 28, a horizontal friction disk 34 is fixed as by a locking nut as shown in FIG. 3, to its lower end 30 and coacts with a vertical friction disk 35 which is fixedly mounted on shaft 36 of a reversible motor M for driving the lead screw 28 in either direction of rotation.

The top and bottom plates 26 and 27 of carriage 25 are interconnected by a front panel 37 which has upper and lower metal inserts or receptacles 38 and 39 disposed in apertures formed therein for receiving respectively an upper green light G¹ and a lower red light R¹ which correspond in position with the main traffic lights G and R of FIG. 1. The bulb receptacle 38 is provided with a pair of terminal posts 40—40 and the bulb receptacle 39 is provided with a pair of terminal posts 41—41 for receiving wires or electrical connections from elements to be described.

A plurality of fixed conductors 42, 43, 44 and 45 extend longitudinally of housing 12, as shown in FIG. 4, and spaced transverse strips of insulation 46 are interposed between the conductors and the rear wall 22 of the auxiliary housing 12. The conductors are fixedly secured by means of screws 47 which are countersunk in the front face of the conductors and the conductors provide an inner pair 43 and 45 and an outer pair 42 and 44. As shown in FIGS. 3 and 5, bolts 48 extend through the upper end portions of inner conductors 43 and 45 and have nuts 49—49 at their rear ends for securing connectors 50 from a switch 51 which controls current from a power source.

Movable conductors 52, 53 and 54, shown in FIGS. 3 and 4, are secured to the underface of the plate 26 of carriage 25 by means of bolts 55 and are positioned to be in constant physical contact with the fixed conductors 42, 43 and 44 during movement of the carriage 25.

Connectors 60—61—62 and 63 interconnect the bulb receptacles 38 and 39 with the movable conductors 52, 53 and 54. As shown in FIG. 3, connector 60 joins movable conductor 52 with one terminal 40 of receptacle 38. Connectors 61 and 62 join movable conductor 53 with the other terminal 40 of receptacle 38, and with terminal 41 of receptacle 39, while connector 63 joins movable conductor 54 with the other terminal 40 of

receptacle 39. Thus, the fixed conductors 42, 43 and 44 are arranged to be in circuit with the lights G¹ and R¹ through the movable conductors and the lights are energized alternately and for predetermined time durations by a mechanical arrangement to be described. As shown in the lower portion of FIG. 4 the fixed conductors 42, 43 and 44 are respectively provided with wires 64, 65 and 66 for connection to the terminals of motor M and it is to be understood that suitable relay or switch means may be provided to reverse the motor for changing the direction of travel of the carriage 25.

The arrangement for alternately supplying power to the lights G¹ and R¹ in accordance with the direction of travel of the carriage 25 resides in the provision of upper and lower transverse rocker arms 70 and 71 shown in FIG. 4, each of which is mounted for limited pivotal movement. To this end the upper arm 70 is mounted in a slot 72 formed in the conductor 45 by a nut and bolt assembly indicated at 73 which permits vertical adjustment of the arm 70 in the slot and also provides for the limited pivotal movement of the arm 70. The lower arm 71 is mounted only for limited pivotal movement by a nut and bolt assembly 74 extending through an insulation strip 46 and the back 22 of the housing 12. The rocker arms have their right end portions interconnected by a vertical rod 75 which is threaded at its upper and lower end portions for reception in apertured lugs 76-77 extending from the rocker arms and adjustably mounted by means of adjusting nuts 78-79.

The upper end portions of conductors 42 and 44 are slotted similarly to the conductor 45 and adjustably receive L-shaped elements 80 and 81 having lower contact lugs 82 and 83 and the elements 80 and 81 are secured in the slotted conductors 42 and 44 by adjusting bolts 84 and 85. The carriage 25 is provided with upper and lower extensions or arms 90 and 91 which are respectively secured by screws 92 and 93 to the upper and lower plates 26 and 27 of the carriage and physically abut or contact in alternation the left side of the transverse rocker arms 70 and 71 as the carriage 25 is moved to its upper limit and lower limit by the lead screw 28.

With the above details of structure in mind, the following general explanation of the operation of the invention should be readily understood.

When the switch 51 is closed power is supplied to the inner or power conductors 43 and 45, to the motor M through connector 65 and one side of lights G¹ and R¹ through the spring contactor 53 and connectors 61 and 62 and to one or the other of the outer conductors 42 or 44 through the transverse arm 70. One or the other of movable conductors 52 or 53 will be energized in accordance with the direction of travel of the carriage 25, through contact of the transverse arm 70 with one of contacts 82 or 83, and the other side of lights G¹ or R¹ will be energized. The conductor 42 will be energized through the contact 82 during one direction of movement of the carriage 25 and light G¹ will be on while the conductor 44 will be energized during the other direction of movement of the carriage 25 and light R¹ will be on.

The time of travel of the carriage 25 in either direction will be synchronized with the operation of the lights G and R of the traffic signal 10. The travel time of carriage 25 is made variable through adjustment of the lugs 80 and 81, the transverse arm 70 and the connecting rod 75 for the purpose of synchronizing lights G¹ and R¹ with lights G and R.

By provision of the auxiliary housing and time lapse indicating mechanism of the invention a pedestrian will be apprised of the approximate time he has to cross an intersection by merely observing the relative position of the light G¹ or R¹ in the housing whereas with the usual street traffic signal there is no positive way to estimate the length of time before a light change.

In FIG. 6, power from a source is supplied by lines X and Y to the traffic signal lights G and R through the

customary automatic timing switch 100 which is set to operate the lights G and R alternately and during selected time periods. To this end wires 101 and 102 are connected with the light R while wires 103 and 104 are connected with the light G from switch 100. The time lapse light R¹ has direct connections 105 and 106 with the wires 101 and 102 while the time lapse light G¹ has direct connections 107 and 108 with the wires 103 and 104 which provide for operation of the light R¹ only while light R is operating and for the operation of light G¹ only while light G is operating.

In order to reverse the direction of movement of the carriage 25, a switch 110 is mounted on the carriage and lines 111 and 112 interconnect the switch with the power lines X and Y while pairs of leads 113-114 and 115-116 are connected between the switch 110 and motor M. Cooperating stops 117 and 118 are mounted on the rear wall 22 of the auxiliary housing 14 and operate to reverse the operation of motor M and to transfer power from one of lights G¹ or R¹ to the other. The stops 117 and 118 will be adjustable, for example, as shown and explained in connection with FIG. 3 in order to be synchronized with the timed operation of the lights G-R. The switch 110 is provided with a pivoted arm 119 which is actuated upon contact with the stops 117 or 118 at the upper or lower limit of movement of the carriage 25 to reverse motor M and to change power between lights G¹ or R¹. By this arrangement it is apparent that in case of a burn out of either of the lights G or R, the auxiliary lights G¹ or R¹ could function to control traffic.

The modification of FIG. 7 is adapted for uses other than for traffic signals and is generally like FIG. 3, differing therefrom in details of construction. This modification provides a unit which is arranged to be plugged into an electrical outlet and may be used for timing machine operations or could be inexpensively constructed and used as a toy. The carriage 25 is provided with a vertical partition 120 providing inner and outer compartments 121 and 122. A switch as 110 in FIG. 6 having a pivoted switch arm 119 is supported on the vertical partition and disposed in the outer compartment 122 and pairs electrical connections 123-124 and 125-126 extend across the inner compartment 121 between the switch and the G¹ and R¹ lights respectively. Other pairs of electrical connections 113-114 and 115-116 extend from the switch 110 to the motor M, as shown in FIG. 6. The top and bottom plates 26 and 27 of the carriage 25 form slots or spaces 127 and 128 with the rear wall 22 of housing 14 and permit passage of the upper and lower stops 117 and 118 into the outer compartment 122 of the carriage 25 to contact the pivoted switch arm 119 for reversing operation of the motor M and the alternate operation of the lights G¹ and R¹. The L-shaped bracket 31 is reversed from its position shown in FIG. 3 in order to provide for uninterrupted movement of the carriage to its lowermost position to provide contact between the lower stop 118 and switch arm 119. A second switch 130 is mounted on the outer wall 22 of housing 14 and is provided with a cord and plug assembly 131 for insertion in an electrical outlet. Connections 132 and 133 extend between switch 130 and switch 110 and are contained within the outer compartment. It will be understood, of course, that the wire connections will be coiled or compactly arranged or be of the extensible type in order to permit movement of the carriage 25 and associated elements.

It will be obvious to one skilled in the art that various changes may be made to the present disclosure without departing from the invention which is limited only by the appended claims.

I claim:

1. A traffic signal having standard Go and Stop lights, main power supply lines and a set of switch controlled conductors for each of the lights, in combination a time lapse indicator comprising a housing having side walls,

including a transparent face and upper and lower end walls, a rotatable lead screw mounted longitudinally of the housing between its end walls, a carriage having top and bottom plates providing a space therebetween, said plates being interconnected by a front panel and supported by said lead screw, a pair of longitudinally spaced light receptacles on the front panel of the carriage, one receptacle having an auxiliary Go light therein and the other having an auxiliary Stop light therein, connections between the one receptacle and the set of conductors of one standard light, other connections between the other receptacle and the set of conductors of the other standard light, a switch supported by the carriage and having connections to the power supply lines, a pivoted control arm for said switch having a free end disposed adjacent one wall of the housing, a reversible motor in the housing operatively connected to the lead screw for reciprocating the carriage within the housing, said top and bottom plates having edge portions positioned to cooperate with a wall of the housing to maintain the carriage panel aligned with the transparent face of the housing during the carriage reciprocation, a first set of electrical conductors between said switch and motor, a second set of electrical conductors being the switch and motor, a first stop on said one wall of the housing spaced from one of its end walls, a second stop on said one wall of the housing spaced from its other end wall, said free end of the pivoted control arm during movement of the carriage in one direction contacting said first stop to deenergize one set of electrical conductors and energize the other set and during movement of the carriage in its other direction contacting the second stop to energize the one set of electrical conductors and deenergize the other set.

2. A time elapse indicator for use with a traffic signal having standard Go and Stop lights, main power supply lines and a set of switch controlled conductors for each of the lights, said indicator comprising a housing having side walls including a transparent face and upper and lower end walls, a rotatable lead screw mounted longitudinally of the housing between its end walls, a carriage having top and bottom plates interconnected by a front panel and supported by said lead screw, a pair of longitudinally spaced light receptacles on the front panel of the carriage, one receptacle for receiving an auxiliary Go light and the other for receiving an auxiliary Stop light, connections from the one receptacle for attachment to the set of conductors of one standard light, other connections from the other receptacle for attachment to the set of conductors of the other standard light, a switch supported between the carriage plates and having connections for attachment to the power supply lines, a pivoted control arm for said switch disposed between the carriage plates and having a free end adjacent the rear wall of the housing, a reversible motor in the housing operatively connected to the lead screw for reciprocating the carriage within the housing, said top and bottom plates having

5 rear edge portions positioned adjacent the rear wall of the housing to maintain the carriage panel aligned with the transparent face of the housing during the carriage reciprocation, a first set of electrical conductors between 10 said switch and motor, a second set of electrical conductors between the switch and motor, a first stop on the rear wall of the housing spaced from one of its end walls, a second stop on the rear wall of the housing spaced from its other end wall, said free end of the pivoted 15 control arm during movement of the carriage in one direction contacting said first stop and during movement of the carriage in its other direction contacting the second stop.

3. A time lapse indicator for a street traffic signal 20 which comprises a housing having end walls and side walls including a transparent face, a lead screw mounted longitudinally of the housing between its end walls, a carriage having top and bottom plates interconnected by a front panel and supported by said lead screw, a reversible motor in the housing, connections between said lead screw and motor for moving the carriage longitudinally of the housing, said carriage panel having a pair of longitudinally spaced light receptacles therein, one receptacle 25 for receiving a lamp of one color and the other for receiving a lamp of another color, said top and bottom plates providing a space therebetween and having rear edge portions positioned adjacent the rear wall of the housing to maintain the carriage panel aligned with the transparent face of the housing, a pair of fixed inner power conductors and a pair of fixed outer power conductors extending longitudinally of the housing adjacent its rear wall, one of said inner conductors pivotally mounting a transverse conductor arm, said outer conductors each having a contactor lug extending therefrom, an 30 inner movable conductor means and a pair of outer movable conductor means mounted in said space between the carriage plates, said inner movable conductor means providing an electrical connection between the other of said fixed inner conductors and each of said receptacles, 35 one of said pair of outer movable conductor means providing an electrical connection between one of said outer fixed conductors and one of said pair of receptacles and the other of said outer movable conductor means providing an electrical connection between the other outer fixed 40 conductor and the other of said pair of receptacles, said reversible motor being connected to said other inner fixed conductor and to each of said outer fixed conductors and means on the carriage operative to pivot said transverse arm in contact alternately with the contactor lugs carried 45 by the outer fixed conductors.
